UNITED STATES PATENT OFFICE.

ALFRED P. BABCOCK, OF NEW YORK, N. Y., ASSIGNOR TO JESSE OAKLEY, JOHN A. OAKLEY, AND E. BENEDICT OAKLEY, ALL OF SAME PLACE.

DESIGN FOR A PERFUMERY-BOTTLE.

SPECIFICATION forming part of Design No. 12,902, dated April 25, 1882.
Application filed March 13, 1882. Term of patent 3 $\frac{1}{2}$ years.

To all whom it may concern:

Be it known that I, ALFRED P. BABCOCK, of the city, county, and State of New York, have invented a Design for a Perfumery-Bottle, of which the following is a specification.

The invention relates to improvements in designs for perfumery-bottles.

In the accompanying photographic illustration a view of my improved design is presented.

The design consists in a conventionalized representation of a lantern the frame or exterior part of which is of the configuration shown, and which serves to protect the bottle containing the perfumery.

The bottle A is in the form of a flask, secured in place by mechanical means which need not be herein described, and has its upper portion reduced to form a neck, which enters the upper section of the frame.

B is the base or lower part of the frame of the case, and C the upper part or section, which presents the appearance of a bell, as shown, surmounted by a knob of fanciful configuration. The base B in outline is formed with a view of producing an ornamental effect. It has also a flat upper surface, upon which the flask A, which is of appropriate and peculiar form, is placed. The bell C, surmounted by the dome-shaped knob, adds essentially to the effect of the whole. The parts B and C are connected by frame-work D, and the upper part, C, is provided with a ring or bail, E, which is bowed as shown.

What I claim as my invention, and desire to secure by Letters Patent, is—

The design for a perfume-bottle hereinbefore described, consisting of the bell C, surmounted by a dome-shaped knob, the base B, of fanciful configuration, the flask A, and frame D, substantially as set forth.

Witness my hand this 8th day of March, A. D. 1882.

ALFRED P. BABCOCK.
